UNITED STATES PATENT OFFICE.

JAMES Q. DAVIS, OF WINNSBOROUGH, AND NEWTON O. PYLES, OF CORONOCO, SOUTH CAROLINA.

BLOTTER.

SPECIFICATION forming part of Letters Patent No. 290,668, dated December 25, 1883.

Application filed October 25, 1882. (Model.)

To all whom it may concern:

Be it known that we, JAMES Q. DAVIS, of Winnsborough, Fairfield county, State of South Carolina, and NEWTON O. PYLES, of Coronoco, Abbeville county, State of South Carolina, both citizens of the United States, have invented a new and useful Improvement in a Blotter; and we do declare that the following is a full, clear, and exact description of the invention, which will enable other skilled in the art to which it appertains to make and use the same.

Figure 1 is a top view of the invention, Fig. 2 a longitudinal sectional view, and Fig. 15 3 a cross-sectional view.

We take a thin metal plate, A, Fig. 1—say about ten inches long and three inches wide—larger if desired. Across this plate, near each end, is a narrow slot, *b*, through which the ends 20 of the blotting-paper *c* are inserted from the lower side, as shown in Fig. 2. Covering these slots are narrow metal strips, with about one-eighth ($\frac{1}{8}$) of an inch at each end bent at a right angle and fastened to the plate A, 25 forming cap *e*, which turns the end of the blotting-paper as it is inserted through the slot and holds it securely in place. The caps also strengthen the plate where the slots are cut. Along the edges on the upper side of plate A 30 is a scale, *d*, measuring inches and fractions

thereof. The blotting-paper is about one-quarter ($\frac{1}{4}$) of an inch narrower than the plate A and the edges of the plate projecting over it, and, being held by it above the surface intended to be ruled, become available as 35 rulers, and, being left clear, may be used as paper-cutters. In the center of plate A is a small knob-handle, *f*.

We claim as our invention and desire to secure by Letters Patent—
40

1. The blotter herein shown and described, consisting of the plate A, having slots *b* in its ends, and raised caps *e*, covering said slots, as and for the purpose set forth.

2. The device herein shown and described, 45 consisting of the plate A, which carries the narrow blotting-paper, said plate having slots *b* and raised caps *e*, and the edges of the plate extending beyond the blotting-paper, whereby they serve as a paper cutter, ruler, and 50 measuring-scale.

JAMES Q. DAVIS.
NEWTON O. PYLES.
